DESIGN FOR A GRILLE FOR WINDOWS AND THE LIKE

Robert H. Hutchinson, Dallas, Tex.

Application June 19, 1937, Serial No. 69,906

Term of patent 3½ years

To all whom it may concern:

Be it known that I, Robert H. Hutchinson, a citizen of the United States, residing at Dallas, in the county of Dallas and State of Texas, have invented a new, original, and ornamental Design for a Grille for Windows and the Like, of which the following is a specification, reference being had to the accompanying drawing, forming part thereof.

Figure 1 is a front elevational view of a grille for windows and the like showing my new design; and

I claim:

The ornamental design for a grille for windows and the like, as shown.

ROBERT H. HUTCHINSON.
